CARTON AND BLANK FOR FORMING THE
SAMEHenry Kondolf, New York, N. Y., assignor to
Southern Kraft Corporation, New York, N. Y.,
a corporation of Delaware

Application June 2, 1933, Serial No. 673,939

8 Claims. (Cl. 229—27)

My present invention relates to a folded display portable partition carton and blank therefor. The object of my invention is to eliminate disadvantages of present methods of shipping tin 5 or case goods, and to provide means to pack articles such as cans, jars or other containers in a portable partition carton made from an integral blank.

The reason for the development of my present 10 invention is that under present methods of packing case goods, particularly when packed in tins, it is impossible to deliver the packages in perfect condition. Cans or tins quite often reach the retail store in a damaged condition. This is 15 noticeable by the fact that the can is often dented, scratched, or otherwise mutilated in such a way that it is impossible to sell the can at regular retail prices, or that the contents are spoiled. Quite often the label is mutilated or completely 20 torn away resulting in loss of attractive value or complete impossibility of sale due to lack of knowledge of the type of foodstuff enclosed. Dents in the tin or can sometimes result in such 25 a change of pressure on the contents that the seams or joints are separated and the contents spoiled, not to mention the fact that leakage damages the labels of other cans.

My carton is made from an integral blank of 30 cardboard, strawboard or other material, preferably of the type known as single or double-faced kraft corrugated board, the latter material being strong, rigid and relatively thin for its 35 stiffness. With my invention a maximum of protection is afforded the articles without appreciable waste of material or use of loose packings such as excelsior or sawdust. One feature of my invention is that each article is retained in a nest or compartment which prevents it from 40 being damaged by knocking against others. The rigid requirements of common carriers are fully satisfied by my carton.

My carton provides means for packing preferably two or three containers, a feature that is extremely desirable in stores which specialize 45 in combination package sales. In connection therewith my carton is so formed that a plurality of articles are packaged as one saleable unit which is easily grasped and carried away by the customer. Articles so packaged are 50 played to the consuming public while retained in a neat carrying package.

A further object of my invention is to afford means for packaging articles without the use 55 of expensive packaging machinery such as stapling or sewing units, my carton being self-

retained without so much as an adhesive strip being required to seal it.

My invention is formed from an integral blank cut and creased in a press and shipped in flat form to the user. An advantage of this form 5 of carton is that the blanks may be shipped on common carriers under the rates applicable to flat sheets, which is lower than that imposed upon formed articles. Another advantage obtained by my invention is that the carton blank 10 is formed without appreciable waste, it being cut from a large sheet of material in such manner that the edges of each blank form the edges of adjacent blanks without loss of material therebetween. 15

My carton is not limited to the packaging of 20 tin goods, it being of such form that fragile containers such as are in common use are completely protected therein. The carton as formed is self-sustained and may be packed in tiers without 25 crushing the enclosed articles, allowing the packaging of open trays or baskets of fruit, berries or even short stemmed flowers. Bags of nuts and other commodities may likewise be shipped 30 in my carton without danger thereto. 25

The preferred form of my invention is illustrated in the accompanying drawing and a detailed description thereof given in the following specification.

Referring to the drawing wherein like numerals refer to like parts:

Figure 1 is a plan view of the blank as shipped to the consumer,

Figure 2 is a perspective view of the assembled 35 carton,

Figure 3 is a sectional view of the carton taken along line 3—3 of Figure 2, showing an enclosed article in skeleton outline, and

Figure 4 is a partial perspective of the blank 40 with the partition flaps assembled.

Figure 1 illustrates the blank showing the relatively small percentage of waste involved in cutting it from a large sheet of material. The bottom of the carton is indicated at 1, side walls 2 and 3 being attached thereto along score lines 45 4 and 5 respectively. Top flaps 6 and 7 are attached to side walls 2 and 3 respectively along score lines 8 and 9. The end edges of flaps 6 and 7 are cut away on lines 10 and 11, the cuts beginning at diagonally opposed corners of the 50 flaps and extending inward to median points thereof. Locking tabs 12 and 13 extend past the median toward these same corners and are spaced from cuts 10 and 11 by notches 14 and 15. Side walls 2 and 3 have tabs 16 and 17 formed 55

therein, said tabs being triangular in shape and formed by diverging cuts along two sides thereof, the divergent ends of the cuts being joined by score lines parallel to score lines 8 and 9.

- 5 A set of tray-forming members are attached to bottom 1 along score lines 20 and 21. These members consist of end flaps 22 and 23, and side flaps attached thereto along score lines parallel to, but slightly inward from, score lines 4 and 5.
- 10 Side flaps 24 and 25 are connected to end flap 22, and side flaps 26 and 27 to end flap 23. The side flaps are separated from the side walls by straight cuts 28. Rounded portions may be removed from the side walls by cutting along lines 15 29 if desired, for a purpose which will be explained. Side flaps 24 and 27 are identical in shape and form, but are diagonally opposed so that side flap 27 is adjacent to side wall 2, while side flap 24 is adjacent to side wall 3, and each 20 flap has a notch 30 therein extending from a median point into cut 28. Side flaps 25 and 26 are identical but diagonally opposed, and have partition flaps 31 attached thereto along score lines, and notches 32 extending from a median 25 point to their outer edges.

The blank having been sufficiently described the method of assembling it into the carton will now be set forth. End flaps 22 and 23 are first bent upwardly along lines 20 and 21. Side walls 30 24 and 26 are now bent inward, parallel to line 5 but slightly inwardly thereof, flap 24 being outside of and overlying flap 26. The end of flap 24 is now brought inward, notches 30 and 32 registering and locking the flaps together. This 35 process is repeated with flaps 25 and 27, flap 25 being locked inward of flap 27, by the registering of notches 30 and 32 therein. Partition flaps are now bent normal to flaps 25 and 26, the flaps being brought into such relationship that each 40 opposes the normal tendency of the other to resume a position in a straight line with its attached side flap.

It is apparent that there is now formed a shallow tray having a plurality of nests formed 45 therein, each nest being adapted to receive therein a single article and restrain it from contact with others. It is equally apparent that members 31 may be so bent by the carton assembler that three nests or compartments are 50 formed, each nest being defined by one of the partition-forming members instead of the two combined as in Fig. 4.

The carton may be so proportioned that the 55 enclosed articles are of the same height as the assembled carton (such as the articles shown at A, Figure 3) and should now be placed in the nests of the tray. Partition members 31 prevent the articles from knocking together and breaking. If the articles are of a lesser height 60 they can easily be inserted later, their presence not being necessary to retain the carton as formed.

Side walls 2 and 3 are now bent upward along score lines 4 and 5 enclosing the tray therein, 65 and top flaps 6 and 7 are bent inward along lines 8 and 9. By a simple twist of the top flaps and side walls, locking notches 14 and 15 are interengaged, locking tabs 12 and 13 underlying the opposite top flaps 7 and 6 respectively and cuts 10 and 11 form a straight continuous 70 diagonal line across the top of the carton as seen in Fig. 2. The locking tabs 12 and 13 are thus protected from accidental tearing or disengagement and the outside surface is neat and unmarred by irregular lines.

Where the usual round tins or containers are being packaged the tabs 16 and 17 are now bent inward to a position substantially normal to the side walls, completing the spacing and protecting features of my invention. The tabs may be so positioned by the operator simply placing his hand over the top of the carton and pressing inward upon the tabs with his thumb and fingertips, sufficient pressure being exerted if desired to slightly deform the tabs and thus doubly securing them between the containers. The top wall of the carton prevents the containers from tilting and falling out through the open display ends while partition members 31 and tabs 16 and 17 prevent lateral shifting of the containers 15 toward each other. End flaps 22 and 23 effectively prevent lateral shifting of the containers through the open display ends of the carton.

The inherent stiffness of the material retains the carton so locked and it is impossible for the 20 tabs to be accidentally released, yet a simple twist of the side walls and top flaps will open the carton when desired.

The package so formed makes an efficient display unit, both enclosed articles being open to 25 view. The cutaway portions 29 enhance this feature, but the ends of sides 2 and 3 may be straight if desired.

Articles when sold in this manner do not need 30 to be wrapped or placed in bags but can be carried away as they are simply by placing the hand over the carton and gripping its sides. The fingertips may be engaged in the openings left by the inward displacement of tabs 16 and 17, thus preventing slippage and assuring a firm 35 grip. This feature is equally present where the usual round type of container is not enclosed, the tabs usually give sufficiently to allow a slight inward bulge below the attaching score lines 40 thereon which will form a hold for the fingertips.

Larger articles may be packed in cartons of 45 larger dimensions, flaps 16 and 17 in such case affording a hand hold on either side of the carton. The sides and top of the carton may carry printed matter or labels and the carton may be 50 wrapped in cellophane or other transparent material.

As is obvious to those skilled in the art my invention may be modified and the several parts rearranged without departing from the spirit of my 55 invention, the scope of which is set forth in the following claims which are to be construed broadly. In using the terms "end", "side" and "bottom" in the appended claims, it is not intended to limit the invention to the particular relative dimensions and positions shown in the drawing, the terms "end" and "side" being used simply to differentiate between the adjacent and non-adjacent portions, the ends being nonadjacent to each other and adjacent to the sides; and the term 60 "bottom" being used simply as a means of differentiating between the panels making up the carton.

What I claim is:

1. A blank adapted to be formed into an open 65 ended carton, comprising a bottom, side walls attached thereto along score lines, a top flap attached to each side wall along a score line, the edge of one top flap being cut diagonally inwardly along a line from one corner to a median point 70 and to form a tab extending from said median point toward said corner, the edge of the other flap being cut diagonally inward along a line from the corner diagonally opposed to said first corner to a median point and to form a tab ex- 75

- tending from said median point toward said second corner, tray-forming members comprising end flaps attached to said bottom along score lines and a pair of side flaps attached to each of 5 said end flaps, and compartment-forming members attached to at least two of said side flaps.
2. An open ended display carton comprising a shallow tray having article-retaining compartments, side walls integral with the bottom of said 10 tray and extending to a greater height than said tray, the end edges of said side walls being cut away to afford a greater display of enclosed articles.
3. An open-ended display carton comprising a shallow tray having article-retaining compartments, side walls integral with the bottom of said tray and extending to a greater height than said tray, and triangular tabs bendable from said side walls adapted to prevent enclosed articles 20 from knocking together.
4. An open-ended display carton comprising a shallow tray having article-retaining compartments, side walls integral with the bottom of said tray and extending to a greater height than said tray, 25 and tabs struck from said side walls adapted to be imposed between adjacent enclosed articles.
5. A carton comprising a rectangular body panel, panels extending from opposite edges of 30 said body panel to form walls along such edges, flaps extending from each side of said wall panels, said flaps being adapted to interlock and form walls along the edges between said first-mentioned edges, one of the pairs of diagonally opposed flaps having extensions adapted to be bent inwardly and form partitions upon said body panel, each of said partitions having the outer 35 surface of its free end portion bearing against the portion of the said other partition adjacent the wall from which the latter extends, walls extending from other edges of said body panel and adapted to be positioned exterior to and extend beyond said previously mentioned walls and having a top member above said body panel.
6. A carton comprising a rectangular body panel, panels extending from opposite edges of 40 said body panel to form walls along such edges, flaps extending from each side of said wall panels, said flaps being adapted to interlock and form a cover above said body panel, said exterior walls having tabs struck from them adapted to be imposed between articles placed in said carton.
7. A carton comprising a rectangular body panel, panels extending from opposite edges of 45 said body panel to form walls along such edges, flaps extending from each side of said wall panels, said flaps being adapted to interlock and form walls along the edges between said first-mentioned edges, one of the pairs of diagonally opposed flaps having extensions adapted to be bent inwardly and form partitions upon said body panel, each of said partitions having the outer surface of its free end portion bearing against the portion of the said other partition adjacent the wall from which the latter extends, walls extending from other edges of said body panel and adapted to be positioned exterior to and extend beyond said previously mentioned walls and form a cover above said body panel, said exterior walls having tabs struck from them adapted to be imposed between articles placed in said carton.
8. A blank for forming a carton comprising a substantially rectangular sheet of material cut and scored to provide a bottom panel, panels extending from opposite edges thereof and flaps extending from opposite edges of said panels, said panels and flaps being foldable to provide a tray, panels extending from other opposite edges of said bottom panel and foldable over and extending beyond said tray, at least one edge of one 50 of said last-mentioned panels being provided with a cut-out area adapted to provide in the completed carton a display area for articles placed in said carton.

HENRY KONDOLF. 45
